TUB SET

William C. McClaskey, New Philadelphia, Ohio,
assignor to Reeves Steel and Manufacturing
Company, Dover, Ohio, a corporation of Ohio

Application February 7, 1939, Serial No. 255,107

4 Claims. (Cl. 248—151)

The invention relates to a tub set or standard for supporting a single tub or two or more tubs connected together as a unit.

The object of the improvement is to provide a standard for supporting one or more tubs, and comprises a plurality of identically similar legs and co-operating clips for supporting a single tub or two or more tubs connected together as a unit.

Another object is to provide a universal leg and universal clip adapted for connection in one position to support a single tub and connection in another position for attaching two or more tubs together.

A further object is to provide a supporting leg having a hooked upper end for engagement over the bead at the top edge of a tub and a clip adapted to be detachably connected to said leg for engagement with the bottom of the tub.

A still further object is to provide a leg having spaced hooks at its upper end for engagement over the beads of two adjoining tubs, and a clip detachably connected to the leg for engagement with the chime portions of the two adjoining tubs to attach the tubs together.

Still another object is to provide a leg having a hooked portion at its upper end for engagement over the bead of a single tub and having spaced hooks at right angles to said hooked portion for engagement over the beads of two adjoining tubs.

Another object is to provide a clip for attachment to the leg adapted to be placed in one position for engagement with the chime of a single tub and to be placed in another position for engagement with the chimes of two adjoining tubs.

A further object is to provide means for interlocking two of said clips together for attaching two adjoining tubs.

A still further object is to provide a modified form of clip for attaching two adjoining tubs together by means of hook bolts.

The above objects together with others which will be apparent from the drawings and following description or which may be later referred to may be attained by constructing the invention in the manner illustrated in the accompanying drawings in which—

Figure 1 is a perspective view of a single tub supported by the improved legs and clips;

Fig. 2, an enlarged fragmentary sectional view showing the manner in which the upper hooked end of one of the legs is engaged with the bead of a tub;

Fig. 3, a similar view showing the clip attached to the leg and engaging the chime of the tub;

Fig. 4, a section taken substantially on the line 4—4, Fig. 3, showing the leg and clip attached to a round tub;

Fig. 5, a similar view showing the attachment of the leg and clip to a corner of a square tub;

Fig. 6, a vertical fragmentary sectional view through the central portions of two legs and through two interlocked clips positioned to attach two adjoining tubs;

Fig. 7, a perspective view showing two tubs connected together and supported by the improved legs and clips;

Fig. 8, a section taken substantially on the line 8—8, Fig. 6;

Fig. 9, a detached perspective view of one of the improved clips;

Fig. 10, an enlarged fragmentary elevation of the upper end of one of the improved legs;

Fig. 11, a fragmentary view of the upper portion of the blank from which the leg is made;

Fig. 12, a perspective view of a modified form of clip for attaching two adjoining tubs together; and

Fig. 13, a fragmentary sectional view of adjoining portions of two tubs attached together with the modified form of clip.

Similar numerals refer to similar parts throughout the several views.

The invention contemplates the provision of a standard or support for a single tub or a plurality of connected tubs, and consists generally of a leg and a clip arranged to be detachably connected thereto, and so constructed that when attached together in one position a plurality of these legs and clips will support a single tub and when attached together in another position a pair of these legs and clips will join two tubs together.

The improved leg forming a major part of the invention is indicated generally at 20 and may be formed of fairly heavy gauge sheet metal and is preferably of channel cross-sectional shape throughout the greater part of its length as indicated at 21, the lower end thereof being of tubular form as indicated at 22 for attachment of a caster as indicated at 23.

The upper portion of the leg may be flat as indicated at 24 and provided with the central upwardly tapered corrugation or rib 25 which is a continuation of the channel portion 21 of the leg.

The upper end of the leg is bent outward at a sharp angle, as shown at 26 and is then bent forwardly and downwardly terminating in the substantially half-round hooked portion 27.

Transversely disposed notches 28 are formed in the underside of the hooked portion 27 near opposite ends thereof, forming hooks 29 at the ends thereof.

5 Each leg has, at a point spaced below its upper end, an angularly disposed portion 30 having an aperture 31 therein provided to receive a bolt 32 for attaching the clip to be later described.

The clip forming a part of the invention may 10 be formed of a fairly heavy gauge sheet metal and may be of the general shape shown in Fig. 9. The body portion 33 of the clip is substantially flat and the opposite side edges thereof may be slightly concaved as indicated at 34 and provided 15 with the angular flanges 35.

A central opening 36 is provided in the body portion 33 to receive the bolt 32 in one position of the clip as will be hereinafter described in detail.

20 One end of the body portion 33 may be tapered as at 38 and terminates in the substantially half-round hook 39, the end portion of which is bent downward and offset below the normal plane of the body portion 33 as indicated at 40.

25 The body portion 33 of the clip is cut out at 41 directly adjacent to the hook 39 in order to receive a portion of a similar hook of another clip in one position, in which the clips are arranged as will be later described in detail.

30 A wing 42 extends outwardly from the other end of the body portion 33 at an obtuse angle, and is provided with a central aperture 43 to receive the bolt 32 in one position of the clip.

This wing terminates in a substantially right 35 angular flange 44 having an edge 45 shaped to fit the curvature of the chime of a round tub as shown in Fig. 4 and provided with the rounded corners 46 shaped to engage in the corner of a square tube as shown in Fig. 5.

40 To support a single tub, three of the legs and three of the clips, as above described, may be connected to the tub T at equally spaced points as shown in Fig. 1.

To attach each leg to the tub the hooked upper 45 end 27 of the leg is engaged over the bead B of the tub as shown in Fig. 2, and the leg is then swung inwardly to the position shown in Fig. 3, contacting the side of the tube and rigidly supporting the same from the bead B to the chime C, the upper portion of the side wall of the tub, 50 which is engaged by the upper end portion of the leg being sprung slightly inward as shown in Fig. 3.

A clip, such as above described and illustrated 55 in Fig. 9, is then placed in the position shown in Fig. 3 with the flange 44 thereof contacting the bottom wall W of the tub and the hook portion 39 of the clip received within the channel portion 21 of the leg as shown in Figs. 3 and 4, and a bolt 32 is then inserted through the aperture 31 in the leg and the aperture 36 in the body portion 33 of the clip, and a nut 47 is placed upon the threaded lower end of the bolt and tightened so as to draw the clip tightly against the leg 60 and bottom wall of the tub forcing the arcuate edge 45 of the flange 44 of the clip tightly against the inside of the chime C of the tub as shown in Fig. 4.

Where these legs and clips are used for supporting a single square tub of the general type 70 shown in Vogan Patent No. 2,084,467, four legs are used, one at each corner of the tub.

The legs and clips are positioned and attached in the same manner as above described and when the nut is tightened upon the bolt rounded cor-

ners 46 on the edge of the flange 44 of the clip are drawn tightly against the chime C' of the tub T' as shown in Fig. 5.

Where two tubs are to be attached together two legs and clips may be attached to each tub 5 in the manner about described and in the position indicated at A in Fig. 7.

The tubs are connected together and supported at their adjoining sides by two similar legs and clips located in the position indicated at A' in Fig. 7.

For this purpose two of the clips are located in the position shown in Figs. 6, 7 and 8 and interlocked by means of the hook portions 39, and, if desired, a bolt as indicated at 48 may be located through the two interlocking hooked end portions of the clips for binding the two clips more rigidly together.

The two clips are located in position as best shown in Figs. 6 and 8 with the body portions 20 thereof in a horizontal plane and the flanges 35 extending upwardly and engaging the chimes C of the two adjoining tubs when the tubs are positioned as shown in Fig. 7 with their rim beads B in contact with each other.

The two legs used for connecting the two tubs together are placed in the position shown at A' in Fig. 7 with the notches 28 at the upper ends of the legs hooked over the beads B of the two tubs.

The bolts 32 are then located through the apertures 31 in the legs and through the apertures 43 in the wings 42 of the clips and the nuts 47 are placed upon said bolts and tightened drawing the clips tightly against the legs and against the chimes of the tubs and locking the hooked upper ends 29 of the legs tightly over the beads B of the two tubs.

From the above it will be seen that both the legs and clips are of universal construction so 40 as to be used for either supporting a single tub or for supporting multiple tubs in the position shown at A, or for attaching two tubs together in the position shown at A'.

Where the tubs are of heavy construction the 45 central support afforded by the two legs in the position shown at A' may be dispensed with, and the two tubs may be tied together by means of the device shown in Figs. 12 and 13 which comprises an attaching clip 49 formed of fairly heavy 50 gauge sheet metal and having the arcuate upstanding flanges 50 at its side edges for engagement beneath the chimes C of the tubs, down-turned strengthening flanges 51 being preferably formed at the ends of this clip and transversely 55 disposed strengthening corrugations 52 being formed through its central portion.

A pair of vertically disposed bolts 53 are located through openings 54 near opposite ends of the clip 49 and are provided at their upper ends 60 with the double hooked heads 55, which engage over the rim beads B of the two tubs.

When the nuts 56 are tightened upon the lower threaded ends of these bolts the two tubs are 65 tightly clamped together between the hooked heads 55 of the bolts and the clips 49.

Although only two tubs are shown connected together by the legs and clips to which the invention pertains it should be understood that any number of tubs may be connected together in 70 this manner.

The tubs may be provided with drain cocks 75 by means of which the contents may be drained therefrom in usual manner, and the bottom walls of these tubs may be raised at the center and in-

clined toward the periphery so that the drain cocks may be located at the peripheral edges of the tubs as illustrated.

I claim:

- 5 1. A support for a plurality of sheet metal tubs including sheet metal legs each leg being of channel cross-section throughout a portion of its length and having a flat upper portion off-set outwardly at its upper end and terminating in a forwardly and downwardly disposed hook adapted to receive and engage over the rim bead of one of the metal tubs, a sheet metal clip associated with each leg and comprising a flat body portion arranged to be inclined downwardly and outwardly and having a reduced lower end portion arranged to be received in the channel of the leg, an angular flange at the upper end of the clip adapted to fit against the bottom wall of the tub and having a curved edge fitting with-
20 in the chime of the tub, a downwardly inclined bolt located through the leg and through the inclined body portion of the clip for detachably connecting the leg and clip to the tub, sheet metal legs placed edgewise between adjacent tubs and having
25 tapered upper edges for contact with the walls of the tubs and having spaced hooks at their upper ends for engagement over the rim beads of adjacent tubs, sheet metal clip means having curved, upright flanges engaging within the chimes of the adjacent tubs and means for detachably connecting said sheet metal clip means to said last named legs.
30 2. A support for a plurality of sheet metal tubs including sheet metal legs, each leg being of channel cross-section throughout a portion of its length and having a flat upper portion off-set outwardly at its upper end and terminating in a forwardly and downwardly disposed hook adapted to receive and engage over the rim bead of one of the metal tubs, a sheet metal clip associated with each leg and comprising a flat body portion arranged to be inclined downwardly and outwardly and having a reduced lower end portion arranged to be received in the channel of
35 the leg, an angular flange at the upper end of the clip adapted to fit against the bottom wall
40

of the tub and having a curved edge fitting within the chime of the tub, a downwardly inclined bolt located through the leg and through the inclined body portion of the clip for detachably connecting the leg and clip of the tub, sheet metal legs placed edgewise between adjacent tubs and having tapered upper edges for contact with the walls of the tubs and having spaced hooks at their upper ends for engagement over the rim beads of adjacent tubs, a pair of sheet metal clips each having a flat body portion with oppositely curved, upright flanges at its side edges engaging within the chimes of the adjacent tubs, interengaging hooks upon the opposed ends of the last named clips, angular wings upon the opposite ends of said last named clips, and inclined bolts located through the wings and last named legs.

3. A support for a plurality of sheet metal tubs including sheet metal legs placed edgewise between adjacent tubs and having tapered upper edges for contact with the walls of the tubs and having spaced hooks at their upper ends for engagement over the rim beads of adjacent tubs, sheet metal clip means having curved, upright flanges engaging within the chimes of the adjacent tubs, means for detachably connecting said sheet metal clip means to said legs, and legs attached to the remote sides of the tubs.

4. A support for a plurality of sheet metal tubs including sheet metal legs placed edgewise between adjacent tubs and having tapered upper edges for contact with the walls of the tubs and having spaced hooks at their upper ends for engagement over the rim beads of adjacent tubs, a pair of sheet metal clips each having a flat body portion with oppositely curved, upright flanges at its side edges engaging within the chimes of the adjacent tubs, interengaging hooks upon the opposed ends of said clips, angular wings upon the opposite ends of said last named clips, inclined bolts located through the wings and legs attached to the remote sides of the tubs.

WILLIAM C. MCCLASKEY. 45
